(57) **CLAIM**

We claim the ornamental design for a vacuum cleaner, as
shown and described.

DESCRIPTION

FIG. 1 is a front, top, left perspective view of a vacuum
cleaner, showing a new design;

FIG. 2 is a front, top, right perspective view thereof;

FIG. 3 is a rear, top, right perspective view thereof;

FIG. 4 is a rear, top, left perspective view thereof;

FIG. 5 is a front, bottom, right perspective view thereof;

FIG. 6 is a front, bottom, left perspective view thereof;

FIG. 7 is a rear, bottom, left perspective view thereof;

FIG. 8 is a rear, bottom, right perspective view thereof;

FIG. 9 is a front side view thereof;

FIG. 10 is a rear view thereof;

FIG. 11 is a right view thereof;

FIG. 12 is a left view thereof;

FIG. 13 is a top view thereof; and,

FIG. 14 is a bottom view thereof.

Broken lines in the drawings are for the purpose of illustrating
portions of the vacuum cleaner that form no part of
the claimed design.

1 Claim, 13 Drawing Sheets
